UNITED STATES PATENT OFFICE.

JOHN O. DE WOLF, OF CAMBRIDGE, MASSACHUSETTS.

METHOD OF MAKING METALLIC PRINTING-PLATES.

No. 905,155.

Specification of Letters Patent.

Patented Dec. 1, 1908.

Application filed July 18, 1906. Serial No. 326,713.

To all whom it may concern:

Be it known that I, JOHN O. DE WOLF, a citizen of the United States, residing at Cambridge, in the county of Middlesex and 5 State of Massachusetts, have invented an Improvement in Methods of Making Metallic Printing-Plates, of which the following description, in connection with the accompanying drawings, is a specification, like numerals on the drawings representing like parts.

The object of my invention is primarily to save time in making printing plates for the modern newspaper office, although it will be understood that its range of usefulness is much more extensive. Besides this 15 primary object, I accomplish accuracy, neatness, economy and various other advantages, which will appear in the course of the more detailed description.

20 In modern newspaper work by far the most important item is to save time in getting out the printed page, and accordingly every energy and facility of the entire plant, regardless of expense are commonly bent to the one object of speed or economy of time; and as at present practiced the most aggravating delay usually occurs in the stereotyping room. It is customary now first to set the type with a linotype machine, then 25 make a papier mâché matrix therefrom and when the latter has hardened, bend it to the proper curvature within a mold or casting box, clamp it in place, closing the casting box, and then pour the molten metal. After 30 the latter has cooled sufficiently to permit of opening the mold, the casting box is opened, the matrix is unlocked and is then stripped off. The stereotyped plate is next taken out, or, in some cases, both the plate and 35 matrix are removed together and afterwards separated. Then the stereotype plate is finished, this process usually consisting of removing the surplus metal at the edges and ends, properly finishing the same so that 40 they will fit on the cylinder of the printing press, and finally the back of the plate is shaved to a true form. The exact order of 45 these operations varies somewhat, but the above sets forth with practical correctness 50 the operations and amount of work commonly employed. It will be seen that time is wasted at each operation in waiting for the completion of one part of the process before commencing the next part and that 55 also much time is lost in waiting for the metal to cool and in shaving the back to fit

the cylinder, etc. Accordingly it is my object to save all this wasted time.

The present application relates to my new method, only sufficient apparatus being 60 shown for properly presenting the method, the apparatus and article herein set forth being expressly reserved for separate applications. In the first place, I aim to use less metal and thus obtain in less time a properly 65 solidified plate. In the next place I maintain a molten or plastic condition of the metal at a given locality only, and progressively shift said locality or region over the matrix until the entire printing surface has 70 been formed. Preferably this forming region or heated locality and application of the heated metal in such a condition as to be properly impressed by the matrix progresses evenly and continuously from one 75 edge of the matrix to the other, and I also prefer to employ molten metal for the purpose. In the third place I gain time by performing, previous to the setting of the type or forming the printing face, as much 80 as possible of the necessary preparation of the back and edges of the plate, it being understood that delay prior to the setting of the type is unimportant, the need of haste occurring after the news has been set in 85 type. Fourthly, I not only perform the operations progressively, as above mentioned, but I perform simultaneously some or all of the operations.

In the most complete embodiment of my 90 invention I bring together progressively the moldable metal *i. e.* the stereotype metal rendered impressionable by heat, and the matrix in the presence of a chilling medium, so that the metal, either molten or semi-molten, obtains its form or type impression 95 from the matrix along a progressive line, or narrow region, and is at once caused to set. In other words, the molding or impressing of the printing plate and cooling 100 or setting of the metal both take place along a narrow region or line progressively from one side of the plate to the other. In this connection I prefer to employ as thin a layer of metal as possible in order that it may receive shape, cool, etc., with the greatest rapidity and accuracy. This enables me to eliminate the danger of shrinking and inaccuracy which has heretofore been due to the employment of a large body of metal; 110 and because of this feature of my invention I have succeeded in eliminating entirely

the necessity of shaving the back of the plate to fit the press. To this end I employ a back which has been previously prepared, having its back and edges accurately shaped before-hand, and on this previously prepared back I form a thin face of proper metal such as stereotype metal, which is progressively molded and shaped or impressed against and by the matrix and simultaneously secured 10 to the back, set and shaped.

I prefer to accomplish the above results by means of rotary apparatus so that all the steps of the process can proceed together. To this end, in the most complete carrying 15 out of my invention, I feed the matrix and the prepared back simultaneously forward and pour the molten metal between them, so that the three come together simultaneously and are immediately brought under 20 the influence of a water jacket or other cooling means which instantly brings the metal to a plastic or impressionable condition, and, having progressed a sufficient distance to cool sufficiently, the matrix is stripped, preferably automatically, from the united back and cast face, said stripping, cooling, pouring and molding all going on simultaneously and progressively, so that when the pouring 25 of the metal is just being finished, the stripping of the matrix has already been largely accomplished.

My method differs from what is known in the art as stereotype plate casting, in that I do not cast the plate, but, instead thereof, I 30 deliver to a matrix progressively a line or narrow area of impressionable metal, and then instantly and permanently impress it with the desired type form or shape, whereupon it is ready, so far as its permanent 35 type surface is concerned, to leave the matrix. The impressing is not done in free-flowing metal, as it would be impossible to leave any impress in a very fluid substance, but is done on the plastic, doughy, or very 40 sluggishly molten metal, *i.e.*, the metal must be sufficiently soft to be capable of being forced into the back and impressed at the front by the matrix, and sufficiently fixed or non-molten to be self-supporting and retain 45 its shaped condition. In making a casting, the metal flows transversely past the adjacent portion of the mold until it has filled up the mold, and then it undergoes a complicated cooling and shrinking process 50 in the mold which finally results in a duly shrunken cast plate. My method differs radically from this casting method, as I do not flow any metal whatever transversely past the shaping surface of the matrix, but 55 first bring the metal to an impressionable or partially cooled or set condition, and then bring the metal and matrix perpendicularly together with a compressing movement 60 which impresses the metal surface directly 65 and permanently with its ultimate shape.

This impressing of the metal takes place along an exceedingly narrow area which I have termed a line, and then immediately the next line or narrow area is similarly impressed, and then the next, and the next, and so on progressively until the entire plate has been formed by a continuous succession of these definite impressing movements of the matrix perpendicularly into the softened, but not liquid, metal.

My invention embodies various other important features, which will be more properly apprehended in connection with a description of the apparatus.

In the accompanying drawings I have shown a sufficient portion of my apparatus to enable me to explain the method clearly, it being understood that a large mass of details are omitted to prevent confusion thereof with the description of the method.

In the drawings, Figure 1 is a central, longitudinal section of the simplest form of apparatus for carrying out my invention; Fig. 2 is a similar sectional view, considerably enlarged, showing the leading steps of the method in progress; Fig. 3 is a sectional detail similar to Fig. 1, excepting that it shows the position of the parts as they are delivering the completed plate and ready to begin operations in making the next plate; Fig. 4 is a view in end elevation of the parts shown in Fig. 3; Figs. 5 and 6 are longitudinal sectional views of the water-cooled portions of the apparatus, Fig. 5 being a substantially vertical section and Fig. 6 a nearly horizontal or oblique section for showing the various cooling passages, and also showing the shape of the edges, etc., of the compound printing plate as it is being formed.

I will briefly describe the apparatus in order that the method may be more clearly understood. Mounted on a suitable base or frame 1 is a rotary cylinder 2 journaled at 3 in heavy uprights 4 and operated by any convenient means as by a worm 5 and worm wheel 6 driven by an electric motor or other source of power 7 shown as controlled by a rheostat lever 8. Fig. 5, adapted to be automatically tripped by a lug 9 and latch 10 or any other usual or preferred tripping mechanism for automatically stopping the machine. At the lower right-hand corner or side of the apparatus, see Fig. 1, is a water-cooled concave surface 11 for coöperating with the cylinder 2, and at the left thereof extending between the uprights 4 is a stripper blade or other stripping means 12 just above a transfer table 13 pivoted at 14 to the base 1 and normally held horizontal by a latch 15 operated by a handle 16, and adapted to be tilted into the dotted position Fig. 1, for the purpose of delivering the stripped matrix to a conveyor 17 so that it will be in position for the operator to re-

place it in the machine for making a separate printing plate. The matrix 18 is placed in a delivery device or hopper 19, which I face with asbestos or other shield 20 for preventing the same from being injured by the heat which is in front thereof. I have herein illustrated my preferred method of carrying out my invention, in which I use metal which is actually molten, and accordingly I deliver the metal 21 from a nozzle 22 of a pipe 23 through which the metal is pumped or otherwise delivered from a suitable source 24, herein shown as being delivered by gravity, a valve 25 controlling the inlet. Above the pipe 23 I preferably provide heating means, herein shown as gas jets 26 for keeping the metal in a highly fluid condition at the very point of delivery. The cylinder 2 is provided with a water-jacket or suitable cooling means 27 over that portion which is to receive the molten metal, and at the forward end of said portion I provide a transverse block 28 which also performs the office of a dam or stop for the metal, as will presently be explained, over which the forward edge 29 of the matrix is adapted to be bent and clamped automatically by any suitable mechanism, such for instance as is commonly employed in printing presses, being herein shown as consisting of clamps 30 on a rod 31, provided externally with a gear 32 operated by a toothed sector or rack 33 pivoted at 34 to the cylinder and held under downward tendency by a spring 35 as well as by its own gravity, said sector rack having a shouleder engaging surface 36 for traveling on a cam ring 37 which has an incline 38 at one portion thereof and a sharp drop or shoulder 39 at another portion thereof, see Fig. 4. Thus when the cylinder is just reaching the position shown in Fig. 3, or rather is just passing forward from the position shown in Fig. 3, the shoulder 36 drops from the shoulder 39 and thereby gives an instant rotary movement to the clamps 30, so that the clamping ends of the latter move in the path shown in dotted lines in Fig. 3 and operate to clamp the forward edge 29 of the matrix tightly over the block 28 as shown in Figs. 1 and 2, holding the same tightly until said part 36 reaches the part 38 of the cam ring, whereupon the clamps are automatically rotated in an opposite direction, thereby releasing the matrix, which because of its comparatively stiff nature and the fact that it has been bent over the angular block 28, springs out away from said block, to be engaged by the stripper 12. This will be explained more at length presently.

The cavity 40 in the concave face 11 is beveled at its ends 41 as clearly shown in Fig. 6, thereby accurately forming the plate to its finished shape. The water jackets are supplied with water by any well-known

means, pipes 42 being indicated for the stationary water-jacket and axial pipes 43 being indicated for the cylinder jacket. The receiving surface of the cylinder is cut away at 44 to receive the back 45 on which the type face is secured and impressed, said cut-away portion 44 cooperating with the recess 40 in the concave shaper or receiving surface. Cooperating with the recess 44 of the cylinder is a stripping mechanism, which may be of any convenient kind, being herein shown as consisting of stripper heads 46 carried by rods 47 reciprocated by bell cranks 48 operated by a shaft 49 located in the cylinder to aline at proper intervals with a plunger 50 pivoted at 51 to a hand lever 52 pivotally mounted at 53 on the frame of the machine.

Let it be supposed that the machine is in the position shown in Fig. 3. The operator takes a back 45 which has been previously prepared so as to be of the exact shape, thickness and curvature desired, it being remembered that this previous preparation may have been performed at any time convenient, and this back 45 he places on the recess 44 of the cylinder in the position shown in Figs. 1 and 4. He then places a matrix 18 in the delivery device 19 and holds it so that its forward end is about in the position shown in Fig. 3. Thereupon he throws the starting lever 8 and the moment that the cylinder is rotated so as to bring the matrix and cylinder together, the clamping dogs 30 are automatically swung from the position Fig. 3 to the clamping position Figs. 1 and 4, thereby clamping the matrix firmly in position so that thereafter the matrix and back move forward together. The moment that the clamping of the matrix takes place the molten facing metal 21 is permitted to flow. This applies a thin face of the stereotype metal on the front of the backing, which is immediately cooled and receives proper impress from the matrix at the point where the back, matrix and metal are forced together by the rotating cylinder. The moment that the impression is made the advance metal and adjacent parts are at once cooled by coming in contact with the water-jacketed former surface or mold 11 and the opposite water jacketed surface of the cylinder. This process continues progressively, the thin metal surface being maintained softened or sluggishly molten at the initial contacting point of the back, metal and matrix, where the metal is simultaneously molded and set in permanent form at said point. This is progressively accomplished over the entire surface. I prefer to move simultaneously the matrix, metal and back, although I wish it understood that my invention includes any movement or progress of the heated impressionable region, the cooling region and the form-

ing region with relation to the matrix, the idea being, in its broader features, to cause the forming of the stereotype progressively over the matrix, or in other words, to render 5 the metal locally impressionable by heat and progressively shift said local condition over the required area of the matrix, at the same time following said locally heated condition with a localized cooling condition until the 10 entire plate has been impressed with the matrix and cooled. Meanwhile as the plate is being thus impressed and formed along one narrow area or line thereof, the matrix and same plate are being elsewhere separated 15 from each other. As shown, where all the parts move together, the cylinder continues rotating forward until the cam surface 36 strikes the surface 38, which thereupon releases the clamping dogs 30 from the forward 20 end of the matrix and the latter springs out away from the block 28 in position to be caught by the stripper blade 12, which operates automatically to remove the matrix progressively from the printing plate 25 as the latter is being impressed and formed. The operation is continuous, without any halting at any point. When the cylinder has arrived at approximately the position shown in Fig. 3, it is automatically stopped 30 by the tripping device 9 or any other suitable stopping mechanism, the operator pushes in the lever 52, which raises the stripper heads 46 and lifts the completed plate, to be carried to the printing press. 35 As the plate has been formed with an impressed surface which is thin and whose cooling begins while it is still under pressure, there is no resulting unevenness due to shrinkage or shifting in position of the 40 metal, and hence no subsequent shaving of the plate, is required in order to bring it to the proper thickness with relation to the backing, both having been formed together as they have moved along in unison. I wish 45 to emphasize the fact just mentioned that the impressing and cooling of the metal take place while the metal and matrix are being pressed toward each other in the act of accomplishing the impressing of the printing 50 surface into the impressionable metal. This is one of the radically new and essential features of my invention which distinguishes it from what is commonly known in the art as casting. No trimming or other treatment is 55 required, as the edges have been properly molded at the same time as the face. The back has previously been prepared with perfect accuracy and the metal is united thereto by any suitable means, as by entering holes 60 54 or dove-tail grooves, scorings, or any other mechanical bond, on the back 45, or the back may be of such consistency as to be slightly fused or amalgamated with the covering surface by reason of the heat of the molten 65 metal. I wish it understood also that my in-

vention includes the union of a facing metal which is not actually melted, but is merely softened at the local region where it is being impressed. I regard it also as broadly novel to form the composite plate with a 70 previously prepared backing, thereby permitting all the necessarily slow back-forming part of the process to be performed previously, when time is not vital. The need for haste all occurs after the matrix is ready, 75 so that whatever work can be done towards the final finished plate previous to the impressing operation is of decided advantage in point of time. By my method, as soon as the matrix is ready, several of the finished 80 printing plates can be prepared quickly without any halting or waiting, directly therefrom. By using a thin face of metal upon a prepared back, not only is there less molten metal to handle and to harden and 85 no back-forming to be done, but extreme rapidity is possible in progressively uniting the face and back at one region while the matrix and plate are being separated at another region from the face already formed. 90 As the molding or impressing is done progressively the metal does not have to flow as heretofore a long distance in a thin mold, and this arrangement makes it feasible to cast a thin and perfect face upon the prepared back. This method of progressive impressing and simultaneous cooling prevents the cooling strains and distortion of the finished plate which take place when a large area is cast and then the same large 100 area is cooled at all points at once. Also by my method I obtain exceedingly sharp definition, which is due no doubt to the compressing of the metal while cooling, or in other words to the perpendicular impressing 105 of the matrix into the metal when the latter is in an impressionable condition, as distinguished from being in a liquid or highly fluid, and hence, non-impressionable condition. The back may be of the same metal 110 as the face, in which case both can be melted together again to be used over again and hence there is no waste, and in this case the weight of the plate is identical with a plate made in the old way; or a different metal 115 may be used for the back, as for instance, aluminum, in which case a very light plate results, an advantage of great convenience in handling when it is borne in mind that the workman is required to handle several 120 tons of these plates per day.

While I have herein shown and described not only the method, but also the apparatus and the composite plate, I wish it understood that the present application is restricted to the method, and that the other features shown and described are reserved for other patents.

I have already mentioned various modifications, and it will be understood that I am 130

not limited to the details herein set forth, as my invention may be carried out in a wide variety of arrangements, steps, and sub-processes.

5 Having described my invention, what I claim as new and desire to secure by Letters Patent is,

1. The method of making printing plates, consisting of juxtaposing the matrix and the 10 plate material rendered locally impressionable by heat, and progressively impressing the plate material and shifting said local condition over the required area until the entire plate is impressed as desired.

15 2. The method of making printing plates, consisting of juxtaposing the matrix and the plate material rendered locally impressionable by heat, progressively impressing the plate material and shifting said local 20 condition over the required area until the entire plate is impressed as desired, and progressively cooling the said plate as it is impressed.

25 3. The method of making printing plates, consisting of juxtaposing the matrix and the plate material rendered locally impressionable by heat, progressively shifting said local condition over the required area until the entire plate is impressed as desired, and 30 meanwhile progressively stripping the matrix from the plate as it is cooled.

35 4. The method of making printing plates, consisting of impressing the plate with the matrix at one portion thereof, and simultaneously stripping the matrix from the plate at another portion thereof.

40 5. The method of making printing plates, consisting of forming and impressing the plate with the matrix at one portion thereof, and simultaneously stripping the matrix from the plate at another portion thereof.

45 6. The method of making printing plates, consisting of progressively forming and impressing the plate, and progressively stripping the matrix therefrom, all as a continuous operation.

50 7. The method of making printing plates, consisting of previously forming a back, then applying thereto an impressionable layer and simultaneously impressing the surface thereof with the matrix.

55 8. The method of making printing plates, consisting of previously forming a back, then applying thereto an impressionable layer, simultaneously impressing the surface thereof with the matrix, and while the latter operation is still in progress beginning to strip off the matrix.

60 9. The method of making printing plates, consisting of previously forming a back, then applying thereto by heat an impressionable layer and simultaneously impressing the surface thereof with the matrix.

65 10. The method of making printing plates, consisting of previously forming a back, then

applying thereto by heat an impressionable layer simultaneously impressing the surface thereof with the matrix, and progressively cooling the impressed surface.

11. The method of making printing plates, 70 consisting of relatively moving a matrix and a layer of type material in an impressionable condition, in progressive forming proximity, with sufficient pressure toward each other to leave a permanent impression 75 of the matrix in the metal while the latter is in a plastic condition, and simultaneously accompanying the said forming step by a progressive cooling operation.

12. The method of making printing plates, 80 consisting of moving a matrix forward, depositing thereon progressively a layer of type material in an impressionable condition as the matrix moves, impressing the matrix into the type metal and cooling the deposited 85 layer while the matrix is still moving.

13. The method of making printing plates, consisting of moving a matrix forward, depositing thereon progressively a layer of type material in an impressionable condition 90 as the matrix moves, applying cooling means, and, while still moving, stripping off the matrix.

14. The method of making printing plates, consisting of relatively moving a matrix and 95 metal in an impressionable condition in such relation to each other as to impress the surface of the metal with the matrix, applying cooling means to the impressed metal after it is impressed, and while it is still moving, 100 stripping the matrix from the cooled plate thus formed.

15. The method of making printing plates, consisting of applying a matrix progressively over the surface of metal reduced to an 105 impressionable condition by heat, immediately cooling said metal after its surface is impressed, and compressing said metal and matrix together while cooling.

16. The method of making printing plates, 110 consisting of progressively forming a printing face on a back previously prepared including impressing said face with a matrix and simultaneously removing the matrix from the completed portion of the face without waiting for the complete forming of the entire printing face of the plate.

17. The method of making printing plates, consisting of moving a previously prepared back between a cylinder and concave mold, 120 and simultaneously feeding in with the moving back a matrix and a surface metal in an impressionable condition between the matrix and back in position to be compressed between the cylinder and mold.

18. The method of making printing plates, consisting of moving a previously prepared back between a cylinder and concave mold, and simultaneously feeding in with the moving back a matrix and a surface metal in an 130

impressionable condition between the matrix and back in position to be compressed between the cylinder and mold, and applying means to said mold for hastening the cooling of the metal.

19. The method of making printing plates, consisting of moving a previously prepared back between a cylinder and concave mold, simultaneously feeding in with the moving back a matrix a surface metal in an impressionable condition between the matrix and back in position to be compressed between the cylinder and mold, applying means to said mold for hastening the cooling of the metal, maintaining constant forward movement, and when the forward portion of the plate is properly cooled, progressively removing the matrix therefrom.

20. The method of making printing plates, consisting of bringing together type metal in an impressionable condition and a matrix perpendicular to each other without relative transverse movement.

21. The method of making printing plates, consisting of bringing together a back, type surface metal in an impressionable condition, and a matrix by a compressing movement perpendicular to the plane of said three parts at the impressing or forming region thereof.

22. The method of making printing plates, consisting of bringing together type metal in an impressionable condition and a matrix with a pressing movement perpendicular to each other sufficient to impress the matrix into the metal without relative transverse movement, and immediately cooling the impressed metal.

In testimony whereof, I have signed my name to this specification, in the presence of two subscribing witnesses.

JOHN O. DE WOLF.
